(57) **CLAIM**

The ornamental design for a spring for vibration motor, as shown and described.

DESCRIPTION

FIG. 1 is a perspective view of a spring for vibration motor; FIG. 2 is a front view of the spring for vibration motor of FIG. 1; FIG. 3 is a rear view of the spring for vibration motor of FIG. 1; FIG. 4 is a left-side view of the spring for vibration motor of FIG. 1; FIG. 5 is a right-side view of the spring for vibration motor of FIG. 1; FIG. 6 is a top plan view of the spring for vibration motor of FIG. 1; and, FIG. 7 is a bottom plan view of the spring for vibration motor of FIG. 1.
